US0D1062189S

(12) United States Design Patent (10) Patent No.: US D1,062,189 S
(45) Date of Patent: * Feb. 18, 2025

(54) FOOTWEAR

- (71) Applicant: adidas AG, Herzogenaurach (DE)
(72) Inventor: Mark Miner, Los Angeles, CA (US)
(73) Assignee: adidas AG, Herzogenaurach (DE)
() Term: 15 Years
(21) Appl. No.: 29/894,484
(22) Filed: Jun. 9, 2023

Related U.S. Application Data

- (63) Continuation of application No. 29/716,695, filed on Dec. 11, 2019, now Pat. No. Des. 1,009,439.

(30) Foreign Application Priority Data

- Jun. 12, 2019 (EM) 006577102
(51) LOC (15) Cl. 02-04
(52) U.S. Cl. USPC D2/969; D2/972
